[57] **CLAIM**

The ornamental design for a large electrical cord extension assembly, as shown and described.

DESCRIPTION

FIG. 1 is a front perspective view of the large electrical cord extension assembly of the present design;

FIG. 2 is a back perspective view thereof; the electrical cord is disclosed in an extended state;

FIG. 3 is a front side elevational view thereof;

FIG. 4 is a back side elevational view thereof; the electrical cord is disclosed in an extended state;

FIG. 5 is a top plan view thereof,

FIG. 6 is a bottom plan view thereof; and,

FIG. 7 is a right hand side elevational view thereof.
